UNITED STATES PATENT OFFICE.

BENJAMIN LIPPER, OF PHILADELPHIA, PENNSYLVANIA.

DESIGN FOR FRINGE.

SPECIFICATION forming part of Design No. 13,976, dated June 12, 1883.

Application filed May 11, 1883. Term of patent 3½ years.

To all whom it may concern:

Be it known that I, BENJAMIN LIPPER, a citizen of the United States, and a resident of Philadelphia, Pennsylvania, have invented or 5 produced a new and original Design for Fringe, of which the following is a specification.

My design is fully shown in the accompanying drawings, Figure 1 being a front view, and Fig. 2 an end view, of a piece of fringe embodying the design, which comprises the two rows of spirally-coiled chenille pendants *a*, one row overhanging the other, but not completely hiding the same. Each pendant consists of a broad central web carrying short transverse threads, which project on each side of the web 15 for a distance equal to or somewhat greater than the width of the latter. As shown, the pendants of the front row are shorter than those of the back row; but I do not consider this 20 essential to the design, as the pendants of both rows may be of equal length. Both rows of pendants are attached to a heading; but the

character of the latter forms no part of the design.

I claim—

1. The design for a fringe, said design comprising the rows of spirally-coiled chenille pendants overlying each other, each pendant having a broad central web and projecting side threads, as shown and described. 25

2. The design for a fringe, said design comprising the rows of spirally-coiled chenille pendants overlying each other, each pendant having a broad central web and projecting side threads, and the pendants of the front row being shorter than those of the rear row, as shown and described. 30 35

In testimony whereof I have signed my name to this specification in the presence of two subscribing witnesses.

BENJAMIN LIPPER.
